UNITED STATES PATENT OFFICE.

CHARLES L. KRUM AND HOWARD L. KRUM, OF CHICAGO, ILLINOIS, ASSIGNEES, BY
MESNE ASSIGNMENTS, TO MOKKRUM-KLEINSCHMIDT CORPORATION, OF CHICAGO,
ILLINOIS, A CORPORATION OF DELAWARE.

TELEGRAPH TRANSMITTER.

Original application filed December 23, 1919, Serial No. 346,948. Divided and this application filed
August 24, 1922, Serial No. 583,975. Renewed May 4, 1927.

The invention relates to transmitters for printing or selective telegraphs and seeks to provide an improved transmitter adapted for use with start-stop telegraph systems, 5 that is to say, a system in which the receiver is provided with a rotary member or distributor which is kept in proper phase relation with the transmitter by being stopped at the end of each signal and again started 10 at the beginning of the succeeding signal.

The invention consists in features of improvement hereinafter set forth, illustrated in the preferred form and arrangement in the accompanying drawings and more particularly pointed out in the appended claims.

The present application is a division of an application filed by us in the United States Patent Office December 23, 1919, Serial No. 346,948.

10 In the drawings:

Figure 1 is a plan view of the improved transmitter;

Fig. 2 is a vertical section on the line 2—2 of Fig. 1 with the motor broken away;

25 Fig. 3 is a detail section on the lines 3—3 of Figs. 1 and 5;

Fig. 4 is a section on the lines 4—4 of Figs. 1 and 5; and

30 Figs. 5 and 6 are detail sections on the lines 5—5 and 6—6 respectively of Fig. 1.

The improved transmitter is mounted upon a base 1 and its rotary member or distributor is driven by a motor 2. If desired, a receiver having a rotary distributor driven by 35 the motor 2 may also be mounted upon base 1. For convenience in assembling the small electric motor 2 is mounted upon a base 4 removably fixed to a plate 5 that is mounted upon the upper face of the base 1. At its 40 inner end the motor shaft is provided with a fly wheel 6 and a suitable governor such as set forth in the application referred to is provided at the outer end of the motor shaft for maintaining the speed of the motor uniform, the governor being provided with means which may be adjusted to obtain the desired rate of speed for the motor.

The base 1 is a hollow casting and has an extension 13 at its lower front portion. The 45 transmitter keyboard comprises finger keys 14 and a space bar 15. The keys are carried upon the upturned forward ends of a set of

levers 16 which are arranged within the upper portion of the base with their forward ends extending outwardly through an opening in the base and over the base extension 13. Front and rear comb bars 17 and 18 are provided for guiding the key levers and the latter are connected to the rear comb bar by a common pivot rod 19. The space bar 15 is mounted on a bail 20 that is pivoted on the upper face of the base extension and engages the downwardly offset forward end of one of the key levers.

The characters are represented by permutations of two different line conditions extending through a definite number of time intervals or units. Preferably a five-interval or five-unit signal code is employed and the signals are represented by permutations either of current and no current or of positive and negative impulses extending through the five intervals or units of each signal.

To selectively determine the signals to be transmitted, the key levers are provided with depending fingers 21 which variably operate a set of five bars or bails 22 that extend transversely below the levers. An additional starting bar or bail 23 is provided and is uniformly operated by all of the key levers. These bails are pivoted on comb blocks 24 fixed in position at the sides of the base 1 and U-springs 25 normally uphold the key levers and bails with the key levers engaging a transverse stop portion 26 at the upper front portion of the base, and with the bails engaging the fingers 21. These springs are provided with hooks at their upper ends which engage the key levers and the arms of the bails and the lower downturned ends of the springs engage an opening in a fixed transverse bar 27. The extent of depression of the key levers and bails is limited by a stop 28, fixed to the bar 27 and projecting forwardly beneath the bails.

The bails 22 are provided at their right-hand ends with arms 29 that project upwardly through an opening in the base 1 and are pivoted to the rear ends of a set of five selecting members or fingers 30. The selecting fingers extend forwardly through guiding notches formed in the upper portion

2
of a common transverse bar 31. Bar 31 preferably forms part of the bail 32, which is mounted on a pivot pin or shaft 33. The latter is mounted in rearwardly projecting arms or lugs 34 formed upon an upright bracket 35 that is fixed to the base 1. An upwardly extending arm 38 on the bail carries an insulated contact 37 that is arranged to engage an insulated adjustable contact 38 on the upper end of the bracket 35. These contacts form a transmitter switch and are preferably normally held in engagement by a spring 39, which extends between the lower portion of the bracket and the depending lug on the bail 32.

A set of five switch shifters is provided for operating the movable contact 37. In the form shown, the switch shifters 40 are provided with U-shaped forward ends which 20 pivotally engage the pin or shaft 33 and their rear ends extend through the guiding notches of the bar 31 and rest upon the forward ends of the selecting fingers 30. At their rear ends the switch shifters are provided with beveled shoulders 41 on their lower edges and with raised lugs 42 on their upper edges, and these shoulders and lugs are arranged to be engaged respectively by the beveled forward ends of the selecting 30 fingers 30 and by a set of five cams 43 which are arranged in a helical series on a transmitter actuating shaft 44.

Shaft 44 is journaled in suitable bearings on the bracket parts 34 and is driven from the motor 2 through the medium of suitable connections controlled by a clutch. In the arrangement shown (see Figs. 1, 2 and 6), the clutch is mounted on a short horizontal shaft 45 which extends from front to rear 40 of the machine and is journaled in two brackets 46 and 47 mounted on the base plate 5. A worm wheel 48 is mounted on the rear end of the clutch shaft and engages a worm 48' on the shaft 49 that is continuously driven, when the machine is in operation, by the motor 2. The forward end of the shaft 45 is connected by a pair of beveled gears 50 of equal size to the transmitter shaft 44, or preferably, as shown, to an intermediate shaft 51, which is journaled in a projecting lug on the bracket 47 and in a bracket 52, on the base plate 5. The intermediate shaft 51 is in line with the transmitter actuating shaft 44 and is connected 50 thereto by a detachable coupling which preferably comprises two disks, 53 and 54, adjustably fixed by set screws to the respective shafts, and one of which is provided with an eccentric pin 55 engaging a notch 60 in the other disk. The worm shaft 48 is in line with the motor shaft and is preferably connected thereto by a similar detachable coupling comprising two disks 56.

The transmitter clutch comprises driving 65 and driven members 57 and 58 having coni-

cal working faces (see Fig. 6). The driving clutch member 57 is in the form of a metal cup and is fixed to the hub of the worm wheel 48. The worm wheel and driving member are loose on the shaft 45 and 70 a yoke 59 fixed to the bracket 46, engages a groove in the hub of the worm wheel and holds it and the driving clutch member against axial movement. The driven clutch member 58 is preferably formed of wood 75 and is fixed to a flanged sleeve 60 that is pinned to the clutch shaft 45. This shaft can shift in axial direction to a slight extent through its bearings 61 and 62 and through the hub of the gear 50 thereon. 80

The forward end of the shaft is squared and engages a corresponding bore in the hub of the gear 50 to drive the latter. This axial movement of the shaft 45 serves to engage and disengage the clutch members. The driven clutch member 58 is provided on its outer face with a cone 63 which is arranged to engage the internal face of an annular brake 64 that is carried on the bracket 47 by means of two pairs of screw pins 65 and 66. 90 The screws 65 extend loosely through openings in the bracket and are adjustably threaded into the body of the brake 64. The screws 66 are fixed to the bracket and the rear ends thereof engage guiding openings 95 in the brake (see Fig. 1). Springs 67 coiled about the screw pins 66 yieldingly hold the brake in position with the heads on the outer ends of the screws 65 engaging the outer face of the bracket 47. By means of the screws 65 the position of the brake and the tension of the springs 67 can be adjusted.

A heavy spring 68 coiled about the forward end of the clutch shaft 45 extends between the flanged bearing 62 and the loose washer 69 which bears against the forward end of the flanged sleeve 60. Preferably, anti-friction rollers are interposed between the washer and the sleeve. This spring tends to shift the clutch shaft rearwardly and move the driven clutch member 58 thereon into operative engagement with the driving member 57. In the normal or zero position, however, the shaft is held by a trip arm or lever 70, in its forward position against the tension of the spring 68 and with the cone 63 of the driven clutch member engaging the brake 64. The trip arm or lever 70 is pivoted at its upper end in a yoke 71 and its lower end engages a guiding yoke 72, both of the yokes being fixed to and projecting rearwardly from the bracket 46. A roller 73 journaled within an opening in the trip lever, engages the rear face of a cam disk 74 that is held by a set screw upon the rear end of the clutch shaft 45 and which is provided with an eccentric lug 75 arranged to co-operate with the roller 73. A locking latch 76 is arranged to engage the lower end of the trip arm 70. This latch is 120

mounted on the horizontal rock shaft 77. The latter is journaled in suitable bearing lugs on the base plate 5 and is provided at its left-hand end with an arm 78 which extends downwardly through an opening in the base and is connected by a link 79 to an arm 80 that depends from the left-hand portion of the starting bar or bail 23.

In the normal or zero position of the transmitter the latch 76 engages the lower end of the trip arm 70 and the roller 73 on the latter engages the cam lug 75 to thereby hold the shaft 45 and clutch member 58 thereon forward with the spring 68 compressed and the cone 63 engaging the brake 64. When any transmitter key is actuated, the starting bar or bail 23 is depressed and latch 76 drawn down to release the trip arm. Spring 68 then serves to quickly engage the clutch members and the transmitter actuating shaft 44 is driven in the direction indicated by the arrows in Figs. 2 and 3. As soon as the cam lug 75 clears the roller 73, a light spring 81 (see Fig. 6) draws the trip arm forward so that it is re-engaged by the latch 76 as soon as the shifted key is restored to normal. The shifted key will usually be restored to normal before the shafts 44 and 45 complete a single revolution. Then, since the trip arm is locked by the latch 76, the engagement of the cam lug 75 with the roller 73 will shift the shaft 45 forwardly and move the clutch member 58 thereon out of engagement with the driving member 57 and into engagement with the brake 64, so that the shafts 44 and 45 are arrested with the flat rear end of the cam lug 75 engaging the roller. This disengagement of the clutch is aided by the momentum of the moving parts and the preferred clutch and brake construction set forth acts efficiently to effect the quick starting and stopping of the transmitter actuating shaft.

As shaft 44 rotates, the cams 43 thereon move in succession over the rear ends of the corresponding switch shifters 40. The lugs 42 on the latter are, however, normally out of the path of movement of the cams 43, but when a key is depressed, one or more of the controlling fingers or selectors 30 are moved forward and lift the rear ends of the corresponding switch shifters so that the lugs 42 thereon are engaged by the corresponding cams 43 as shaft 44 rotates, and this operation of the cam lugs will depress the rear ends of the switch shifters, the forward ends of the selecting fingers, and the common transverse bar 31 of the bail 32 to thereby open the transmitter switch contacts 37 and 38. Shaft 44 is also provided with an additional starting cam 82, which is disposed in advance of the cams 43 and is arranged to engage a lug 83 fixed to the bar 31. Unlike the lugs 42 of the switch shifters, lug 83 lies in the path of its operating cam

and is engaged thereby during the initial portion of each revolution of shaft 44 to shift the transmitter switch contact 37.

The cams 43 and 82 are preferably formed upon separate disks held in place on the shaft by spacing washers 84 and a nut 85, to thereby form in effect a single cylindrical cam member or support, the surface of which is divided into seven equal spaces or unit sections. The cams 82 and 43 extend in succession through six of these spaces, leaving one space unoccupied. The vacant space or gap of the cam supporting member, in the zero position of the transmitter shaft, lies above the lugs 42 of the switch shifters 80 and the lug 83 on the bar 31. At each revolution of the shaft, cam 82, as stated, engages the lug 83 to impart an initial or starting impulse to the line. Cams 43 then pass in succession over the rear ends of the switch shifters 40 and during the interval that each cam passes over the lug 42 of the corresponding switch shifter, the transmitter switch contacts are either opened or closed in accordance as to whether or not the rear end of the switch shifter has been raised by the corresponding controlling finger 30. A starting pulse or interval followed by a permutation of two different line conditions extending through five time intervals or units and representing a character signal, is thus imparted to the line at each revolution of the transmitter shaft.

As shown, the cams 43 and 82 are provided with concentric outer edges and beveled ends, and the beveled ends of adjacent cams terminate in alignment, as most clearly shown in Fig. 3. The lugs 83 and 42, which cooperate with the cams, are correspondingly beveled and the arrangement is such that the starting pulse or interval and the five intervals or pulses of the selective signal code are of uniform length. Also, with this arrangement, two like pulses or line conditions will follow each other with no gaps or spacing intervals between them.

Means are provided for locking the shifted keys and holding the other keys against operation. For this purpose a lock bar 86 extends transversely below the key levers 16 and is provided with a beveled rear edge arranged to co-operate with beveled lugs 87 formed upon the fingers 21 of the key levers. The lock bar is attached to the lower ends of two rock arms 88 which extend upwardly through openings in the base 1, one being pivoted to a lug on the bracket 35 and the other to a bracket 89 on the base. The right-hand arm 88 is provided with an upwardly and rearwardly inclined extension and carries a roller 90 arranged to engage the periphery of the disk 53. A spring 91, connected to the right-hand arm 88, holds the roller in engagement with the disk 53 and

the latter forms a cam for operating the lock bar. This disk is circular through the greater portion of its periphery, but is provided with a recess which is engaged by the roller 90 in the zero position of the transmitter, so that the lock bar 86 is held out of the path of movement of the lugs 87. As soon as the key is depressed, however, the cam 53 shifts the lock bar rearwardly and to engage the lugs 87 and hold the shifted key lever in actuated position and the other key levers against movement. Preferably the cam 53 and lock bar 86 are arranged to co-operate with the beveled lug 87 of the selected key to complete its shift.

At or before the end of one revolution of the transmitter actuating shaft 44 the roller 90 drops into the recess of the cam 53 and the shifted key and parts controlled thereby are restored to normal in readiness for the transmission of the succeeding signal. Preferably, in order to permit rapid operation of the transmitter keyboard, the recess of cam 53 is of such length that the keys are unlocked and restored to normal during the transmission of the third or fourth interval or pulse of each signal, but this necessitates the use of some means for storing the last or the last two impulse selections. In the form shown, the cam recess is of such length that the keys and signal selecting bails or bars are released and restored to normal during the transmission of the fourth pulse of each signal, and means, most clearly shown in Fig. 4, are provided in connection with the fifth impulse controlling finger for permitting the operation of a key during the transmission of the fifth pulse.

The arm 29 of the fifth bail is cut off and is provided with an upwardly extending spring arm 92 to the upper end of which the corresponding controlling finger 30' is pivoted. The latter extends rearwardly of its pivot and a light spring 93 extends between its rear end and the arm 29. The controlling finger 30' is provided near its forward end and on its lower edge with a short lug 94, which normally lies in rear of the bar 31. The fifth impulse cam 42 as shown is provided with an extension 95 of the same length as the other cams but of less height and arranged in line with the fourth impulse cam. When a key which selects the fifth bar or bail 23 is depressed the projection 94 on the corresponding controlling finger 30' will strike against the bar 31, so that the controller cannot be shifted to lift the corresponding switch shifter and the spring arm 92 will be flexed as shown in full lines in Fig. 4. The depression of the key will also, of course, close the transmitter clutch and start the rotation of the shaft 44 and cam 53, thereon, and the latter will shift the locking bar and hold the selected key down, as also indicated in Fig.

4. Then, when the bar 31 is depressed by the engagement of the starting cam 82 with the lug 83, the spring 93 can then slightly lift the forward end of the controller 30' so that the flexed spring arm 92 will shift it forward to the position indicated in dotted lines in Fig. 4, and thereby raise the fifth impulse switch shifter 40. In this position the lug 94 will be in front of the bar 31 and, at the proper time, the fifth impulse cam 42 will engage and actuate the fifth impulse switch shifter.

The locking bar releases the shifted key as soon as the fourth impulse has been transmitted, but the fifth impulse controller 30' is prevented from moving back to normal position—in case the bar 31 is depressed by the fourth impulse cam—by the extension 95 of the fifth impulse cam. This extension holds the controller 30' sufficiently downward to prevent its projection 94 from clearing the bar 31. As spring 93 is much lighter than the spring 39, of the rocking bail 32, its action cannot open the contact. If the fifth bar or bail 23 has been selected for a letter, the controlling finger 30' remains in its shifted left-hand position at the completion of the transmission of the character signal, and the spring arm 92 will be flexed in the opposite direction from that indicated in Fig. 4. If the fifth bar or bail is selected for the succeeding character, the controlling finger 30' remains in shifted position; but, if it is not selected it will slip back over the bar 31 when the starting cam 82 moves the bar downwardly. If desired, similar storing means could be associated with the fourth impulse selecting devices. This arrangement for storing the fifth impulse selections of the code signals permits of the rapid operation of the transmitter in sending a message, and, indeed, without arresting the transmitter shaft, since the keys can be operated so rapidly that before the transmitter and clutch shafts 44 and 45 have completed a revolution the latch 76 will have been shifted to released position and the trip arm 70 will not act to open the clutch. Nevertheless, as the cams 82 and 43 and the spacing portion of the cam member on the shaft 44 pass in succession over the lug 83 and the lugs 42 of the switch shifters, the code signals each preceded by a starting pulse will be properly imparted to the line and will be separated by spacing intervals substantially equal in length to the starting and selecting intervals and during which the line is restored to normal closed condition. Of course, during pauses in the operation of the finger keys, or at the end of the transmission of a message, the latch 76 and trip arm 70 will act as described to arrest the transmitter in zero position, ready for further operation.

It should be noted that the improved

transmitter is operated solely under local control. That is to say, it is started and stopped independently of the line impulses and does not apply the starting impulses to the line until after it leaves or moves through its normal or zero position. In this way the timing of the impulses or intervals of the signals, including the starting interval, is controlled solely by the movement of the rotary transmitter member during each signal period. The rotary member or distributor of any receiver responsive to the line impulses is preferably set to rotate at an angular speed slightly greater than that of the transmitter member so that it will be invariably arrested at the end of each signal and again started in proper phase relation to the signal intervals by the starting interval of the succeeding signal. Since the transmitter applies the starting intervals for the line after it leaves or moves through its zero position it is not necessary to adjust the receivers to take care of any variation in the starting lag of the transmitter.

25 It is also noted that the improved transmitter employs mechanically actuated vibratory transmitting contact means which is less subject to defective operation on account of wear than is the case with an electrical distributor or sunflower.

Changes may be made and the details set forth varied without departing from the scope of the appended claims.

We claim as our invention:—

35 1. In a signalling apparatus, transmitter switch contacts, a set of selectors, a rotary cam member having a series of successively operative sections for effecting the operation of said contacts variably in accordance with the setting of said selectors and thereby transmit a corresponding succession of impulses, a power-driven start and stop clutch for rotating said cam member, a key board and solely mechanical means actuated by said keyboard for setting said selectors and tripping said clutch.

2. In a signalling apparatus, transmitter contacts, a set of selectors, a rotary cam member having a series of successively operative sections for effecting the operation of said contacts to transmit uniform starting impulse followed by a series of selecting impulses varied in accordance with the setting of said selectors, a power driven start and stop clutch for rotating said cam member, and means independent of said transmitter contacts for tripping said clutch and setting said selectors.

3. In a signalling apparatus, transmitter switch contacts, a set of selectors, a rotary cam member having a series of successively operative sections for effecting the operation of said contacts variably in accordance with the setting of said selectors, a start and stop clutch comprising a power actuated driving

member, a brake, and a driven member connected to said cam member and axially shiftable to alternately engage said driving member and said brake, a trip for shifting said driven member into engagement with said brake, a latch for said trip and a key-board for setting said selectors and releasing said latch.

4. In a signalling apparatus, contacts for controlling all transmitted impulses, a set of shifters therefor, a set of selectors for controlling said shifters, a rotary cam shaft having a series of successively operative sections for variably actuating said shifters in accordance with the setting of said selectors, a power driven start and stop clutch for continuously advancing and timing the operation of said cam shaft during each signal period, a keyboard and means operated thereby independently of said transmitter contacts for tripping said clutch and for operating said selectors.

5. In a signalling apparatus, transmitting contacts, a set of shifters therefor, a set of selectors for controlling said shifters, a rotary cam shaft variably actuating said shifters in accordance with the setting of said selectors, a power driven start and stop clutch for rotating and timing the operation of said cam shaft during each signal period, a key board for tripping said clutch and operating said selectors, a lock for said keyboard controlled by said cam shaft and arranged to release said keyboard before the end of the signal period, yielding connections between said keyboard and one or more of said selectors, and means controlled by said cam member for temporarily holding such selectors either in the shifted or retracted position.

6. In an electric signalling apparatus, a transmitter contact, a set of shifters therefor, a set of selectors for variably positioning said shifters, a power driven rotary cam shaft having a starting cam for uniformly operating said contact at the beginning of each signal and a set of cams for variably operating said contact shifters in accordance with the setting of said selectors, said cams being arranged in succession about said shaft with a spacing gap between the terminal cams of the series, means to start said cam shaft at the beginning of each signal and stop the same with said spacing gap in operative position at the end of each signal, and a keyboard for controlling said starting and stopping means and for setting said selectors.

7. In an electric signalling apparatus, a transmitter contact, a set of shifters therefor, a set of selectors for variably positioning said shifters, a power-driven rotary cam shaft having a starting cam for uniformly operating said contact at the beginning of each signal and a set of cams for variably

6
operating said contact shifters in accordance with the setting of said selectors said cams being arranged in succession about said shaft with a spacing gap between the terminal cams of the series, a start and stop clutch for initiating and arresting the operation of said cam shaft at the beginning and end, respectively, of each signal, and a keyboard mechanism controlling said clutch and setting said selectors, said keyboard mechanism being arranged to effect the continuous operation of said cam shaft.

8. In a signalling apparatus, transmitter switch contacts, a power driven rotary cam member having contact operating sections arranged in series about said shaft with a spacing gap between them and brought in order into operative position as said member is rotated, a set of members for selectively controlling the operation of said cam sections upon said contacts, means for starting and stopping said cam shaft at the beginning and end respectively of each signal, and controlling means for said starting means and said selecting members arranged to effect the continuous operation of said member.

9. In a signalling apparatus, transmitter switch contacts, a power driven rotary cam member having contact operating sections arranged in series about said shaft with a spacing gap between them and brought in order into operative position as said member is rotated, a set of members for selectively controlling the operation of said cam sections upon said contacts, a clutch for starting and stopping said cam shaft at the beginning and end respectively of each signal, a keyboard for controlling said clutch and for setting said selecting members, and a lock bar on said keyboard controlled by said cam shaft arranged to permit the continuous operation of said cam member.

10. In a signalling apparatus, transmitter switch contacts, a power driven rotary cam member having contact operating sections arranged in series about said shaft with a spacing gap between them and brought in order into operative position as said member is rotated, a set of members for selectively controlling the operation of said cam sections upon said contacts, means for starting and stopping said cam shaft at the beginning and end respectively of each signal, a keyboard for controlling said starting means and setting said selecting members, and a lock bar for said keyboard controlled by said cam shaft and arranged to release the same before the completion of the signal period to thereby permit the continuous operation of said cam member.

11. In a telegraph transmitter, a rotary cam member, transmitting switch contacts operated thereby for controlling all line conditions, said cam member having a series of

sections brought successively and one at a time into operative position as the member is rotated and including uniformly acting starting and spacing sections at the ends of the series, a set of selectors variably controlling the operation of the intermediate sections, a motor driven start and stop clutch for continuously advancing said cam member during each signal period and for stopping the same with said spacing section in operative position, and means for controlling the operation of said clutch and of said selectors.

12. In a telegraph transmitter, a motor driven rotary cam member, transmitter contacts operated thereby and controlling all line conditions, said cam member comprising a series of sections acting successively and one at a time as said cam member is rotated and including uniformly acting, starting and spacing cam sections at the ends of the series respectively controlling the opening and closing of the contacts, a set of selectors variably controlling the operation of the intermediate cam sections, a stop device for arresting said cam member with the spacing section in operative position, means for tripping said device and for variably controlling said selectors.

13. In a telegraph transmitter, transmitting contacts, a set of shifters therefor, a set of selectors, a power driven rotary cam member having a series of successively acting cam sections co-operating with said shifters to uniformly operate said contacts at the beginning of each signal period, thereafter, under control of said selectors, to variably operate the same and finally to restore said contacts to normal condition at the end of each signal period, means for arresting said cam member with said restoring or spacing cam section in operative position, and means independent of said transmitting contacts for releasing said arresting means and for setting said selectors.

14. In combination with a telegraph transmitter, transmitting contacts, a set of selectors, a power-operated rotary cam member having a series of angularly spaced sections brought successively into operative position as said cam member is rotated and including a starting section for uniformly operating the contacts at the beginning of each signal period and a series of cam sections cooperating with said selectors to thereafter variably operate the contacts, a stop device for arresting said cam member with said starting cam section in inoperative position, and means operative independently of said transmitter contacts for setting said selectors and releasing said stop device.

15. In combination with a telegraph transmitter, a motor-driven rotary cam member, transmitter contacts holding the line closed in a normal rest position of said cam mem-

ber and operated by the rotary movement thereof to thereby control all transmitted impulses, said member having a series of sections acting successively and one at a time as the member is rotated and including starting and spacing sections uniformly acting at the beginning and end respectively of each operation of the cam member, a set of selectors for variably controlling the operation of the other cam sections, a stop device for arresting said cam member with the spacing section thereof in operative position and with other of said sections in inoperative position, and means for variably operating said selectors and for releasing said stop device.

16. In a transmitting apparatus for start-stop telegraph systems, vibratory transmitting contact means normally holding the line closed, a set of controlling selectors therefor, a start-stop actuating member adapted by its movement from a normal rest position and during each signal period, to position said vibratory contact means and thereby establish a starting line condition followed by a definite interval permutation of selecting conditions in accordance with the setting of said selectors, and means for mechanically starting and stopping said actuating member and for conditioning said selectors.

17. In a transmitting apparatus for start-stop telegraph systems, a single vibratory transmitting contact, a set of impulse selectors and a start-stop actuating member adapted by its movement from a normal position and during each signal period, to change the position of said contact and thereby establish a starting line condition followed by a definite interval permutation of selecting conditions in accordance with the condition of said selectors.

18. In a transmitter for start-stop telegraphs, vibratory transmitting contact means, a rotatable actuating member therefor movable successively through a series of positions to thereby condition said vibratory contact means during a corresponding series of successive time intervals including starting and selecting intervals of substantially uniform length and a final spacing interval of at least equal length, a set of selectors for variably determining the line conditions during the selecting intervals, and controlling means for said actuating member operable to arrest and again start the movement thereof only during the spacing intervals.

19. In a transmitter for start-stop telegraphs, vibratory transmitting contact means, a rotatable actuating member therefor movable successively through a series of positions to thereby condition said vibratory contact means during a corresponding series of successive time intervals including start-

ing and selecting intervals of substantially uniform length and a final spacing interval of at least equal length, a set of selectors, said actuator invariably placing said contact means in two different conditions during the starting and spacing intervals respectively, and variably conditioning the same during the selecting intervals in accordance with the condition of said selectors, and controlling means operable to arrest and again start the movement of said actuating member only during the spacing intervals and for variably conditioning said selectors.

20. In a transmitter for start-stop telegraphs, vibratory transmitting contact means, a rotatable actuating member therefor movable successively through a series of positions to thereby condition said vibratory contact means during a corresponding series of successive time intervals including starting and selecting intervals of substantially uniform length and a final spacing interval of at least equal length, a set of selectors for variably determining the line conditions during the selecting intervals, a motor and interposed clutch for continuously advancing said actuating member during the starting and selecting intervals, a cooperating stop device operable to arrest said member only during the spacing intervals, and all mechanical controlling means, including a keyboard, for releasing said stop device and for conditioning said selectors in different combinations.

21. In a transmitter for start-stop telegraphs, a set of selectors, a single transmitting contact, an actuating member therefor movable successively through a series of positions during corresponding starting, selecting and spacing time intervals to thereby place said contact invariably in two different positions during the starting and spacing intervals respectively and variably position the same in accordance with the condition of said selectors during the selecting intervals, and controlling means for arresting and again initiating the operation of said actuating member during the spacing intervals and for conditioning said selectors.

22. In a transmitter for start-stop telegraphs, vibratory transmitting contact means normally holding the line closed, a set of controlling selectors, a rotatable actuating member movable successively through a series of off-normal positions and a normal position during corresponding starting, selecting and spacing time intervals to thereby invariably place said vibratory contact means in two different conditions during the starting and spacing intervals respectively and variably position the same during the selecting intervals in accordance with the condition of said selectors, means for conditioning said selectors, and actuating and controlling means operable to stop said actuat-

- ing member in normal position and to start the same therefrom and adapted to effect the continuous rotation of said actuating member during successive signal periods.
23. In a transmitter for start-stop telegraphs, vibratory transmitting contact means, a set of controlling selectors therefor, a rotary actuating member, means for continuously advancing said member to thereby position and time the operation of said vibratory contact means during each signal period to transmit a start pulse followed by a series of selecting impulses in accordance with the condition of said selectors and for restoring the line to a normal closed condition for a definite interval at the end of each signal, and all mechanical means for starting and stopping said actuating member and for conditioning said selectors.
24. In a transmitter for start-stop telegraphs employing a definite interval signal, a single vibratory transmitting contact, a set of mechanical controlling selectors therefor, a rotatable actuating member having a normal position for holding the contact closed and adapted by its rotary movement from a normal position during each signal period to invariably open said contact during the starting interval of the corresponding signal, thereafter cooperate with said selectors to variably open and close the contact during the selecting intervals, and finally restore the same to normal closed condition at the end of each signal, a plurality of key levers for conditioning said selectors, and means controlled by said key levers and operable independently of said contact for initiating the rotation of said actuating member.
25. In a transmitter for start-stop telegraph systems, a set of selecting elements, a rotary actuating member, vibratory contact means positioned and timed in operation by the rotary movement of said member during each signal period to thereby initially open the line and thereafter variably open and close the line in accordance with the condition of said selectors and finally to restore the line to normal closed condition at the end of each signal, and all mechanical controlling means for conditioning said selectors and for initiating and arresting the operation of said rotary actuating member.
26. In a transmitter for start-stop telegraphs employing definite interval code signals, vibratory transmitting contact means normally holding the line closed, a set of controlling selectors therefor, a start-stop, rotary actuating member movable from a normal position and during each signal period to thereby uniformly position said contact means during the start interval of the corresponding signal and thereafter variably position the same in accordance with the condition of said selectors and to restore said contact means to normal closed condition for at least a definite interval at the end of each signal, and controlling means for conditioning said selectors and for arresting and again initiating the operation of said rotary actuating member between signal periods.
27. In a transmitter for start-stop telegraphs, a single transmitting contact, a set of controlling selectors and a rotary actuating member therefor, a motor and an interposed clutch for continuously advancing said member during each signal period to thereby uniformly position said contact in an off-normal position during a starting interval and thereafter variably position the same in accordance with the condition of said selectors and to restore said contact to normal at the end of each signal, and means for conditioning said selectors in different combinations and for controlling the operation of said clutch.
28. In a transmitter for start-stop telegraphs, a single transmitting contact, a set of controlling selectors and a rotary actuating member therefor, a motor and an interposed clutch for continuously advancing said member during each signal period to thereby uniformly position said contact in an off-normal position during a starting interval and thereafter variably position the same in accordance with the condition of said selectors and to restore said contact to normal at the end of each signal, a stop device for arresting said rotary actuating member at the end of any signal period, and a plurality of key levers for conditioning said selectors and for simultaneously and mechanically releasing said stop device.
29. In a transmitter for start-stop telegraph systems employing definite interval code signals, vibratory transmitting contact means normally holding the line closed, a rotary cam member having a series of sections acting successively, as said member is rotated, to position said contact means during a corresponding series of successive time intervals including starting and selecting time intervals of substantially uniform length and spacing intervals of at least equal length, a set of selectors for modifying the line conditions during the selecting intervals, and start-stop operating and controlling means for said member arranged to arrest the same with the spacing section thereof in operating position and with the line in normal closed condition.
30. In a transmitter for start-stop telegraph systems employing definite interval code signals, vibratory transmitting contact means normally holding the line closed, a rotary cam member having a series of sections acting successively, as said member is rotated, to position said contact means dur-

- ing a corresponding series of successive time intervals including starting and selecting time intervals of substantially uniform length and spacing intervals of at least equal length, a set of selectors for modifying the line conditions during the selecting intervals, means for continuously advancing said cam member during the starting and selecting intervals, and controlling means operating to arrest and again start said member only during the spacing intervals.
31. In a transmitter for start-stop telegraphs, a single vibratory transmitting contact, a set of controlling selectors, a rotary cam member having a series of sections successively acting, as said member is rotated, to position said contact, during a corresponding series of successive time intervals including starting and selecting intervals of uniform length and spacing intervals of at least equal length, the starting and spacing sections of said cam member invariably acting to place said contact in two different conditions, and the other cam sections variably conditioning the same under control of said selectors, and start-stop actuating and controlling means for arresting said cam member with the spacing cam section thereof in operative position.
32. In a transmitter for start-stop telegraphs, a single vibratory transmitting contact, a set of controlling selectors, a rotary start-stop cam member having a series of sections successively acting, as said member is rotated from a normal position during each signal period, to initially open said contact, thereafter variably open and close the same in accordance with the condition of said selectors, and finally restore said contact to a normal closed condition, means for continuously advancing said cam member during each signal period and all mechanical means for conditioning said selectors and for initiating and arresting the movement of said actuating member.
33. In a transmitter for start-stop telegraph systems, vibratory transmitting contact means, a start-stop rotary actuating cam therefor having a series of successively acting sections including invariably acting starting and spacing cam sections at the beginning and end of the series, a set of selectors controlling the operation of the intermediate cam sections, the starting and intermediate sections being of substantially uniform length and the spacing section of at least equal length, a motor and an interposed clutch for operating said cam member and controlling means for arresting said cam member with the spacing section in operative position, said controlling means arranged to permit the continuous rotation of said member during successive signal periods.
34. In a transmitter for start-stop telegraph systems, vibratory transmitting contact means, a start-stop rotary actuating cam therefor having a series of successively acting sections including invariably acting starting and spacing cam sections at the beginning and end of the series, a set of selectors controlling the operation of the intermediate cam sections, the starting and intermediate sections being of substantially uniform length and the spacing section of at least equal length, a motor and an interposed clutch for continuously advancing said cam member during each signal period, a cooperating stop device for arresting the member with the spacing section thereof in operative position and means for mechanically conditioning said selectors and releasing said stop device.
35. In a transmitter for telegraphs, a start-stop rotatable cam member, a set of mechanical elements selectable in different combinations, and a single transmitting contact invariably shifted from normal position during each signal period by the rotary movement of said cam member from its normal rest position and thereafter variably operated by the conjoint action of said member and said elements.
36. In a transmitter for telegraph systems employing definite interval code signals, transmitting contacts, a set of actuating shifters therefor corresponding to the selecting intervals of the signals, a corresponding set of selectors for moving said shifters either to operative or inoperative condition, a rotary cam member for effecting the contact actuating movements of the shifters in operative condition, a motor and an interposed clutch for continuously and uniformly advancing said cam member during each signal period and means for controlling the operation of said clutch and of said selectors.
37. In a transmitter for telegraph systems, vibratory transmitting contact means, a set of mechanically acting shifters therefor, a rotary cam member for effecting the contact operating movement of said shifters one at a time, and means for selectively placing each of said shifters either into or out of position to be operated by said cam member.
